UNITED STATES PATENT OFFICE.

OTTO LUNDERSHAUSEN, OF BERLIN, GERMANY.

TOILET-GLASS.

SPECIFICATION forming part of Letters Patent No. 510,076, dated December 5, 1893.

Application filed April 20, 1892. Serial No. 429,875. (No model.)

To all whom it may concern:

Be it known that I, OTTO LUNDERSHAUSEN, a subject of the King of Prussia, German Emperor, and a resident of Berlin, in the Kingdom of Prussia, German Empire, have invented certain new and useful Improvements in Toilet-Glasses, of which the following is a full and exact specification, reference being had to the accompanying drawings, in which—

10 Figure 1 is a front elevation of my improved toilet-glass partly in section. Fig. 2 is a side-elevation of the same. Fig. 3 is a cross-sectional elevation of the same, and Fig. 4 is a sectional plan on line A—B of Fig. 1.

15 My invention relates to a toilet-glass made of three parts, each having a mirror plate, and the outer parts being adapted to turn round a hinge and to fold into a suitable frame.

20 My invention also consists in providing appropriate springs in order to effect an automatic opening of the hinge parts upon pressing a suitable knob, said knob being connected to a catch which locks the parts in their folded position.

25 F is the frame of my improved toilet-glass, said frame being made of wood or metal or any other material. The free space S inclosed by the frame F is of square or rectangular form. The frame may be secured to the wall by means 30 of nails, hooks or by any other means. Toward the rear part of the frame I provide grooves G for receiving the mirror glass M. A short distance in front of the mirror glass M I provide the hinge H for a frame R, said frame being adapted to receive a second mirror-glass M'.

35 The frame R is hinged to the frame F in the following manner: At the top it is connected to the frame F simply by means of a pin P 40 serving as a pivot. About at middle height of the frame R I secure to the same the ends of two flat metal strips T, preferably of steel, for instance by passing them through a small sleeve and soldering them to the same. These 45 flat metal strips T extend downward, passing loosely through a suitable hole O at the bottom of the frame R, and are at their under ends secured to a small plate E embedded in the frame F. The metal strips T act as torsional springs, and are arranged in such manner 50 that they have a tendency to turn the frame R into the open position illustrated by

Fig. 4. On the opposite side of the frame F and directly in front of the frame R, I secure a frame R', having a mirror-glass M², and hinged to the frame F in exactly the same manner as described for the frame R. Finally I provide, in the middle of the frame F, a knob K, which is rigidly connected to a catch C, said catch being pressed upward by a 60 spring I. On the lower side of the frame R' I provide a suitable catch or notch adapted to engage with the catch C. The faces of the frame R' and mirror-glass M² which are turned outward when the toilet-glass is in its folded 65 position, may be decorated by an ornamental pattern or by a picture.

The device, being in its closed position, may be opened by applying a slight downward pressure on the catch C. The frame R' is then 70 released and, being influenced by the spring formed by the metal strips T, turns round the hinge and folds out of the frame F, the frame R following closely. The device then presents a three-fold mirror-surface which is very 75 convenient for toilet use. When it is desired to bring the parts into their first closed position, the frame R is turned round its hinge and folded into the frame F; after this, the same is done with the frame R', and the catch 80 C automatically engages with the catch or notch provided on the under side of said frame, thus locking the parts in the folded position.

Having thus fully described the nature of 85 my invention, what I desire to secure by Letters Patent of the United States is—

In a toilet-glass, the combination with the frame F provided with an open space S, vertical grooves G formed in the rear portion of 90 the sides of the frame, a mirror glass M in said grooves, a second frame R provided with a mirror glass M' and hinged to the frame F within the space S, and at one side of the same, said frame R being adapted to be folded with 95 in the frame F and being provided with an opening O, a third frame R' provided with a mirror glass M² and hinged to the frame F within the space S and at the end thereof opposite to the frame R, said frame R' being 100 adapted to be folded within the frame F over the frame R and being provided with an opening O, flat metallic spring strips T secured at their upper ends to the frames R, R'

and passing loosely through said openings O and secured at their lower ends in the frame F, a spring-actuated catch C carried by the frame F on its lower side and provided with a 5 knob, said catch adapted to engage a notch in the lower side of frame R', as and for the purpose specified.

In testimony whereof I have signed this specification in the presence of two subscribing witnesses.

OTTO LUNDERSHAUSEN.
